UNITED STATES PATENT OFFICE

FRED GIMBEL, OF CHICAGO, ILLINOIS

SERVICE CABINET

Application filed March 25, 1932. Serial No. 601,273.

My invention relates to a service cabinet designed primarily for holding ice cubes and butter cubes until a service thereof is required, but it is to be understood that a service cabinet, in accordance with my invention 5 may be used in any connection for which it may be found applicable.

The essential objects of my invention are to provide, in a manner as hereinafter set forth, a service cabinet for the purpose referred to for holding cubed ice and cubed butter in a sanitary manner, until a service thereof is required; arranged in a manner to contain a refrigerant for the cubed butter; for utilizing the cubed ice as a refrigerant for the cubed butter; overcoming the objection of the cubes of butter sticking together, as is present in the manner now generally employed of holding the cubes, until required for serving, in a bowl-like container; reducing the waste of cubed butter, as is now present, when the cubes are held, until required for serving, in a bowl-like or other open top container as it is well known that not more than 65% of the cubes placed in the container is serviceable; to overcome the direct personal handling of the cubes of butter by the waiters or waitresses when a cube is to be served; providing for the service of a cube of butter directly from a tray carrying the cubes onto the plate of a guest; preserving the flavor of the butter by holding it for service in a condition free of water or ice; preventing the cubes of butter, until required for serving, in a condition of non-exposure to dirt or dust; overcoming the unsanitary method of handling cubed butter now generally employed in hotels, restaurants and institutions; preventing the direct personal handling of ice cubes when the latter are desired to be served; and to attain these ends in a comparatively simple, strong, durable, compact, thoroughly efficient, conveniently handled and inexpensive structure 45 for the purposes as referred to.

To the above ends essentially, and others which may hereinafter appear, my invention consists of such parts, and such combination of parts which fall within the scope of the 50 invention as claimed.

In the drawing:

Figure 1 is a perspective view of a cabinet in accordance with my invention.

Figure 2 is a cross sectional view on line 55 2-2 Figure 3.

Figure 3 is a longitudinal sectional view of the cabinet.

Figure 4 is a perspective view of the form of cubed butter holding tray employed.

The cabinet is of rectangular form and may be of any desired length, width and height, but preferably the length will be a foot and a half, its height one foot and its width substantially corresponding to its height. It is to be understood that there is to be no limitation as to the dimensions of the cabinet.

The cabinet includes a body part 1 formed of an outer, an intermediate and an inner section 2, 3 and 4 respectively. The sections 2 and 4 are formed of sheet metal, and the section 3 of heat-insulating material of greater thickness than the other sections. Each section includes a bottom, a front and a rear wall and a pair of side walls. The sections 2, 3 and 4 in the front walls thereof have aligning cutouts, as at 5, 6 and 7 respectively to provide an opening. The walls of the sections 2, 4 at the top thereof are connected together by a metallic rim 8 to provide a flat edge 9. Secured within section 4 is a transversely disposed partition 10 which forms the body part into a pair of open top compartments 11, 12, the former being arranged 85 rearwardly of the latter.

The cutouts 5, 6 and 7 are of rectangular contour and bearing throughout against the edges or walls of the cutouts is a hollow metallic casing 13 open at its front and rear 90 ends. The casing corresponds in contour to the shape of the cutouts and is shown by way of example as rectangular. The rear end of casing 13 is secured against the front face of partition 10, the latter closing such 95 end. The casing is also secured to the edges of the cutouts of the sections 2, 4. The casing 13 provides a compartment 14 for receiving the cubes of butter. The compartment 11 is for containing the cubes of ice, and the com- 100

partment 12 is adapted to receive a refrigerant to surround the casing 13.

The front end of the casing 13 is closed by an insulated metallic, downwardly swinging door 15, hinged at its bottom as at 16 to the front wall of section 2 below cutout 5. The door 15 is formed at its front with a lateral flange 17 which abuts the outer face of the front wall of section 2 when the door is closed. 10 The door when closed extends into the front end of casing 13 and acts as a closure for the entrance or outer end of compartment 15.

Arranged within the lower portion of compartment 11 is a removable perforated false bottom 18 spaced above bottom 19 of such compartment. The bottom 18 supports the ice cubes above bottom 19 to provide a drain space 19'. Extended forwardly from the upper end of the partition 10 is a support 20. A removable, insulated metallic closure 21 is provided for the open top of compartment 12 and which is formed with a lateral flange 22 seated on edge 9 and support 20. Arranged within the compartment 12 at the front of the lower portion thereof is a filter member 23. Communicating with compartment 12 is a drain cock 24 therefor having its inner end opening into the space provided by member 23. Extending from compartment 11, through compartment 12 and attached to a drain cock 25 is a drain pipe 26 for compartment 11.

The side walls 27, 28 of compartment 14 have the inner face of each thereof provided with a set of superposed, spaced combined guiding and supporting elements 29. The elements 29 on one wall aligning with the elements 29 on the other wall. The elements 29 extend from the partition 10 to a point inwardly of the front end of casing 13 to provide a clearance for door 15 when the latter is shut. Mounted upon each pair of aligning elements 29 is a slideable cubed butter carrying tray 30 provided at a point between the transverse median and outer end with a transverse rib 31 forming a stop for the butter cubes and also preventing one's fingers touching the cubes on the action of removing a tray from compartment 14. That part 32 of the tray extending inwardly from rib 31 is for placing the butter cubes thereon. That part 33 of the tray extending outwardly from rib 31 provides a handle or grip portion. The part 32 is formed with upstanding flanges 34 at the sides thereof.

The door 15 is provided with a latch 35 for detachably maintaining it closed. The compartment 14 is water tight.

The trays 30 are mounted in a manner to permit the ready withdrawal of a selected tray and constructed to enable a cube of butter to slide off therefrom without the cube being handled by one.

The arrangement of compartment 11, rearwardly of compartment 12 permits of the em-

ployment of the ice cubes to assist in cooling compartment 13. The ice cubes can be readily withdrawn by a pair of tongs from compartment 11 and deposited in the glass or tumbler which is to be used by the guest. The butter cubes are not only preserved by the ice cubes, but also by the refrigerant in compartment 12, and such refrigerant is to be arranged to envelop casing 12.

What I claim is:

1. In a service cabinet for cubed ice and cubed butter, an open top body part formed with an opening in its front, a partition in said body part forming front and rear compartments open at the tops thereof, the former for receiving a refrigerant and the latter for storing removable ice cubes, a casing open at each end, abutting at its rear the said partition and secured at its front to the wall of said opening, spaced, superposed, combined guiding and supporting elements secured to the inner faces of opposed walls of said casing, removable, butter tube supporting and serving trays slidably mounted within said casing upon said elements, a door for closing the front of the casing, and a removable closure for the open top of the front compartment.

2. In a service cabinet for cubed ice and cubed butter, an open top body part formed with an opening in its front, a partition in said body part forming front and rear compartments open at the tops thereof, the former for receiving a refrigerant and the latter for storing removable ice cubes, a casing open at each end, abutting at its rear the said partition and secured at its front to the wall of said opening, spaced, superposed, combined guiding and supporting elements secured to the inner faces of opposed walls of said casing, removable, butter cube supporting and serving trays slidably mounted within said casing upon said elements, a door for closing the front of the casing, a removable closure for the open top of the front compartment, a false perforated bottom in said rear compartment, and controllable drainage means for said compartments discharging at the front of the body part.

3. In a service cabinet for cubed ice and cubed butter, a compartment for the storing of removable ice cubes therein, a compartment forwardly of and parallel to said other compartment for receiving a refrigerant, a normally closed water tight compartment for the storing of removable butter cubes therein and surrounded by the refrigerant compartment, removable and slidably mounted means supported in the butter cube storing compartment for holding the butter cubes, and said butter cube storing compartment disposed at right angles to the ice cube storage compartment, the entrance opening for one of said compartments disposed at right angles to the entrance opening for the other of said compartments.

4. In a service cabinet for cubed ice and cubed butter, a compartment for the storing of removable ice cubes therein, a compartment forwardly of and parallel to said other compartment for receiving a refrigerant, a normally closed water tight compartment for the storing of removable butter cubes therein and supported by the refrigerant compartment, removable and slidably mounted means supported in the butter cube storing compartment for holding the butter cubes, said butter cube storing compartment disposed at right angles to the ice cube storage compartment, said storage compartments for the ice and butter cubes having their openings disposed at right angles to each other, a perforated false bottom within said ice cubes storing compartment for supporting such cubes, a removable closure for the refrigerant compartment, and controllable drainage means for the ice cube storing and refrigerant compartments, discharging at the front of the refrigerant compartment.
5. In a service cabinet for ice cubes and butter cubes, a receptacle comprising an insulated open top body part having an opening in its front wall, a vertical partition within said body part providing a pair of parallel vertical open top front and rear compartments, a water tight casing disposed at right angles to said partition, abutting the latter and extending into said opening, said casing having its outer end open and arranged intermediate the top and bottom of the front compartment, said front compartment for the reception of a refrigerant to surround said casing, said rear compartment for the storing of removable ice cubes, removable butter cubes holding trays slidably supported in said casing, a downwardly opening door for closing the outer end of said casing, and a removable closure for said front compartment.
6. In a service cabinet for ice cubes and butter cubes, a receptacle comprising an insulated open top body part having an opening in its front wall, a vertical partition within said body part providing a pair of parallel vertical open top front and rear compartments, a water tight casing disposed at right angles to said partition, abutting the latter and extending into said opening, said casing having its outer end open and arranged intermediate the top and bottom of the front compartment, said front compartment for the reception of a refrigerant to surround said casing, said rear compartment for the storing of removable ice cubes, removable butter cubes holding trays slidably supported in said casing, a downwardly opening door for closing the outer end of said casing, a support at the top of said partition, and a removable closing for said front compartment seating on said support and body part.
7. A service cabinet for ice cubes and butter cubes comprising a structure providing a rear compartment for storing ice cubes, a refrigerant receiving forward compartment and a compartment for storing butter cubes, said compartment for storing the butter cubes being disposed at right angles to the rear compartment and completely surrounded by said forward compartment, said rear and forward compartments being open at the top and the other of said compartments being open at the front of said structure, said rear compartment being permanently open, a removable closure for normally closing the open top of said forward compartment, and a downwardly swinging closure hinged to the front of said structure for normally closing said butter cube storage compartment.
8. A service cabinet for ice cubes and butter cubes comprising a structure providing a rear compartment for storing ice cubes, a refrigerant receiving forward compartment and a compartment for storing butter cubes, said compartment for storing the butter cubes being disposed at right angles to the rear compartment and completely surrounded by said forward compartment, said rear and forward compartments being open at the top and the other of said compartments being open at the front of said structure, said rear compartment being permanently open, a removable closure for normally closing the open top of said forward compartment, a downwardly swinging closure hinged to the front of said structure for normally closing said butter cube storage compartment, and removable butter cube serving means slidably mounted in said butter cube storing compartment for supporting such cubes in the latter.
9. A service cabinet for ice cubes and butter cubes comprising an open top housing, a vertical partition positioned within and forming in connection with the housing a rear open top compartment for the storing of ice cubes and a forward open top compartment for receiving a refrigerant, said housing intermediate the upper and lower ends of its front being provided with an opening, a casing open at each end, said casing secured at its rear end against and disposed at right angles to said partition, said casing extending across said front compartment and into said opening and secured to the walls of the latter, said casing providing an open front compartment for storing butter cubes, said rear compartment being permanently open, a removable closure for said front compartment for normally closing the latter, and a closure hinged to the front of the housing for normally closing the open front of the butter cube storing compartment.
10. A service cabinet for ice cubes and butter cubes comprising an open top housing, a vertical partition positioned within and

formed in connection with the housing a rear open top compartment for the storing of ice cubes and a forward open top compartment for receiving a refrigerant, said housing intermediate the upper and lower ends of its front being provided with an opening, a casing open at each end, said casing secured at its rear end against and disposed at right angles to said partition, said casing extending across said front compartment and into said opening and secured to the walls of the latter, said casing providing an open front compartment for storing butter cubes, said rear compartment being permanently open, a removable closure for said front compartment for normally closing the latter, a closure hinged to the front of the housing for normally closing the open front of the butter cube storing compartment, and removable butter cube serving means slidably mounted in said butter cube storing compartment for supporting such cubes within the latter.

11. A service cabinet for ice cubes and butter cubes comprising a structure provided with means forming parallel independent front and rear vertically disposed compartments having their entrances at the tops thereof and a horizontally disposed compartment having its entrance at its outer end, the entrance of the rear compartment being disposed at right angles to the entrance of the horizontal compartment, said horizontal compartment being surrounded by said front compartment and extending at right angles to said rear compartment, said front compartment for storing a refrigerant to surround said horizontal compartment, said rear compartment for storing ice cubes and being permanently open at its entrance for the removal of ice cubes, a pair of shiftable closures disposed at right angles to each other, one for the entrance of the front compartment and the other for the entrance of the horizontal compartment, and butter cube holding trays slidably mounted in said horizontal compartment and removable therefrom through the entrance of the latter.

In testimony whereof, I affix my signature hereto.

FRED GIMBEL.
